CLAIM

The ornamental design for a light emitting diode (LED) package, as shown and described.

DESCRIPTION

FIG. 1 is a top perspective view of a LED package showing our design according to a first embodiment;

FIG. 2 is a top plan view thereof;

FIG. 3 is a bottom plan view thereof, opposite the view of FIG. 2;

FIG. 4 is a first side view thereof;

FIG. 5 is a second side view thereof;

FIG. 6 is a third side view thereof, opposite the view of FIG. 4;

FIG. 7 is a fourth side view thereof, opposite the view of FIG. 5;

FIG. 8 is a top perspective view of a LED package showing our design according to a second embodiment;

FIG. 9 is a top plan view thereof;

FIG. 10 is a bottom plan view thereof, opposite the view of FIG. 9;

FIG. 11 is a first side view thereof;

FIG. 12 is a second side view thereof;

FIG. 13 is a third side view thereof, opposite the view of FIG. 11;

FIG. 14 is a fourth side view thereof, opposite the view of FIG. 12;

FIG. 15 is a top perspective view of a LED package showing our design according to a third embodiment;

FIG. 16 is a top plan view;

FIG. 17 is a bottom plan view;

FIG. 18 is first side view;

FIG. 19 is second side view;

FIG. 20 is third side view;

FIG. 21 is fourth side view;

FIG. 22 is a top perspective view of a LED package showing our design according to a fourth embodiment;

FIG. 23 is a top plan view;

FIG. 24 is a bottom plan view;

FIG. 25 is first side view;

FIG. 26 is second side view;

FIG. 27 is third side view; and,

FIG. 28 is fourth side view.

The broken lines are for illustrative purposes only and form no part of the claimed design. The stippled portion of the embodiment illustrated in FIGS. 8, 9, 11, and 13 represent that the stippled portion is a different material than other, adjacent portions. The more densely stippled portions illustrated in FIGS. 22, 23, and 25-28 represent a metallic surface.
